UNITED STATES PATENT OFFICE.

ELLSWORTH P. OGDEN, OF COLUMBUS, OHIO, ASSIGNOR TO JOHN B. OWENS, OF ZANESVILLE, OHIO.

TUNNEL KILN.

1,418,669.

Specification of Letters Patent. Patented June 6, 1922.

Application filed November 5, 1920. Serial No. 422,000.

To all whom it may concern:

Be it known that I, ELLSWORTH P. OGDEN, a citizen of the United States, residing at Columbus, in the county of Franklin and 5 State of Ohio, have invented certain new and useful Improvements in Tunnel Kilns, of which the following is a specification.

This invention relates to tunnel kilns and, more particularly, to a means and method 10 whereby flashing conditions at high temperatures may be obtained, for the accomplishment of salt glazing and other special heat treatments without disturbing the normal pyro-chemical conditions in the lower-heated parts of the kiln.

My object is to provide means, and a method, for the production of the desired kiln atmosphere conditions in the maximum temperature zone, of a tunnel kiln where- 20 by flashing, salt glazing, or other chemical treatment of the ware may be obtained when the ware is subject to maximum temperature and yet prevent such treatment of any ware in the tunnel which has not attained a sufficiently high temperature to render it sus- 25 ceptible to the desired chemical treatment.

The object aforesaid is accomplished by the provision of a fan or an auxiliary stack or stacks or other draft-inducing means acting 30 on the firing zone of the tunnel at any suitable point or points, preferably near the zone of maximum temperature, there being suitable damper control, with means whereby the damper or dampers employed for that purpose may be operated substantially at the same time with the operation of a damper in the main draft outlet, and the method there- 35 in involved.

To accomplish flashing, reducing conditions 40 will be produced by supplying excess fuel and limiting the air supply to the combustion chambers. Salt glazing conditions can be produced by the introduction of salt into the combustion chambers and flooding 45 the tunnel with the sodium chloride vapors which unite with the silica in the clay wares undergoing firing and thus produce the salt glaze of commerce. Any other desired chemical treatment of the clay wares may be 50 accomplished by flooding the tunnel with gases or vapors of the desired nature.

The important feature of my invention is that the means and method involved provide for the removal of all such special gases

or vapors from the tunnel before they have 55 an opportunity of coming in contact with any ware in the tunnel which has not attained a sufficiently high temperature to render it susceptible to the desired chemical treatment.

While I have disclosed in the accompanying drawings, and hereinafter describe, certain embodiments of my invention, this is done by way of illustration and not for the purpose of limiting the scope of the invention to these particular embodiments as I am well aware that my improved means and method may be carried out in other forms without departing from the essential principles thereof.

In the accompanying drawings:

Figure 1 is a plan view, partly in section; Fig. 2 is a cross section on line 2—2, Fig. 1;

Fig. 3 is a cross section on line 3—3, Fig. 75 1; and

Fig. 4 is a cross section on line 4—4, Fig. 1.

My improvements are shown as embodied in a tunnel kiln of the multiple combustion chamber and multiple firing zone type invented by John B. Owens and disclosed in certain applications filed by him, in so far as it embodies a preheating zone 1, multiple burning or firing zone 2 and cooling zone 3, there being multiple furnaces or combustion chambers 4, of which there may be any desired number, arranged in pairs, each pair having a continuous arch 5 constituting the crown and outer walls of the combustion 85 chambers. The combustion chambers are fired in the direction of their lengths, that is, parallel to the tunnel. The stack which is shown at 6 is connected to the interior of the tunnel by flues 7 which are provided with dampers 8 constructed and arranged for quick opening and closing. The rails on which the cars travel through the kiln, are shown at 9 and the cars appear at 10.

It is to be understood that while I have 100 disclosed my improvements and method in connection with the "Owens" type of tunnel kiln, I wish it understood that the invention is not limited to use in connection with any particular type or construction of 105 tunnel kiln.

I provide an auxiliary stack or stacks, or draft-inducing means connected with the

tunnel at a suitable point or points of the firing zone 2 but preferably near the zone of maximum temperature. A pair of such stacks is shown at 11, 12, which communicate 5 with the interior of the tunnel through ducts or flues 13, 14. The stacks 11, 12 are provided with dampers 15, 16 adapted for quick opening and closing.

- It is within the spirit of my invention to 10 employ separate operating means for opening and closing the dampers 8 on the one hand, and the dampers 15, 16, on the other hand and to time the operation so that it will be simultaneous. I prefer, however, to 15 connect the dampers 8 with the dampers 15, 16 by hand lines 17 running over pulleys or other supports 18 so that by simply pulling upon these hand lines, simultaneous operation will be effected.
- 20 Under normal conditions the dampers 15, 16 will be closed and the draft through the kiln will be effected by the stack 6 or a fan or whatever draft-inducing means is used, the dampers 8 being operated as desired, as 25 usual in draft control.

To utilize my invention for any of the purposes hereinafter set forth, the operation is as follows: At regular intervals during the firing process and logically during 30 the period just preceding the movement of the cars in the tunnel, the main draft dampers 8 are closed and the auxiliary dampers 15, 16 are opened by pulling on the hand lines 17. This action is accompanied by the generation of the desired kiln atmosphere conditions in the maximum temperature zone, whether this condition be for the 35 purpose of flashing, salt glazing, or other chemical treatment. It is to be understood that the dampers 15, 16, afford means for releasing from the kiln, through the flues 13, 14 and the stacks 11, 12, any special gases or vapors which have been introduced in the 40 kiln for the purpose of special treatment of the ware, such removal being brought about before the gases or vapors come in contact with any ware that has not attained a sufficient temperature to render it susceptible to the desired special treatment. The draft 45 being cut off through the stack 6, the gases and vapors used for special treatment cannot pass down the tunnel far enough toward the entry end thereof to affect ware which has not risen to the proper temperature to 50 warrant the special treatment in question. When the hand lines 17 are operated to close the dampers 15, 16, the operation opens the dampers 8 and the normal draft through the kiln is restored.

60 What I claim is:

1. A tunnel kiln provided with a main stack or fan and also having an auxiliary stack or fan independent thereof by which special gases and vapors which have been introduced into the kiln for special purposes

may be removed therefrom without resort being had to the means for inducing the main draft.

2. A tunnel kiln provided with a main stack or fan and also having an auxiliary 70 stack or fan independent thereof acting on the firing zone of the kiln whereby special gases and vapors which have been introduced into the kiln for special purposes may be removed from the firing zone without resort 75 being had to the means for inducing the main draft before said gases or vapors have the opportunity of coming in contact with ware in other parts of the kiln.

3. A tunnel kiln provided with a main 80 stack or fan and also having an auxiliary stack or fan independent thereof by which special gases and vapors that have been introduced into the kiln for special purposes may be removed therefrom, and draft controlling 85 means for the respective draft-inducing means aforesaid, whereby the draft may be allowed to pursue its normal course, or, be taken off by the auxiliary draft-inducing means to the exclusion of the main draft 90 inducing means.

4. A tunnel kiln provided with means for producing draft therein, and also having auxiliary draft-inducing means whereby special gases and vapors which have been 95 introduced into the kiln for special purposes may be removed therefrom, and controlling devices for the draft producing means and auxiliary draft inducing means which are subject to a common control whereby one of 100 said means may be rendered active when the other is inactive.

5. A tunnel kiln provided with a stack or fan for causing the usual draft therein, and also having an auxiliary stack or fan acting 105 on the firing zone of the kiln whereby special gases and vapors which have been introduced into the kiln for special purposes may be removed from the firing zone before they have the opportunity of coming in contact 110 with ware in other parts of the kiln, and controlling devices for the aforesaid main and auxiliary draft-inducing means which are subject to a common control whereby one of said means may be rendered active when 115 the other is inactive.

6. The method of operating a tunnel kiln, consisting in effecting flashing conditions, salt glazing, or other special heat treatments while the normal draft in the kiln is shut 120 off, and taking off from the kiln the special gases or vapors introduced therein, by means other than the normal draft-inducing means during the time the normal draft is shut off, thereby preventing the special gases or vapors from coming in contact with ware in the kiln which has not reached a condition adapted for the special treatment.

7. The method of operating a tunnel kiln, consisting in effecting flashing conditions, 130

salt glazing, or other special heat treatments while the normal draft in the kiln is shut off, and taking off from the heat zone of the kiln the special gases or vapors introduced therein, by means other than the normal draft-inducing means during the time the normal draft is shut off, thereby preventing

the special gases or vapors from passing beyond the heat zone and coming in contact with ware which has not acquired a sufficiently high temperature adapting it for the special treatment. ¹⁰

In testimony whereof I affix my signature.
ELLSWORTH P. OGDEN.
